CLAIM

The ornamental design for a railing supported elongated planter, as shown and described.

DESCRIPTION

FIG. 1 is a top front right side perspective view of a railing supported elongated planter showing my new design;

FIG. 2 is a top plan view thereof;

FIG. 3 is a front side elevational view thereof; the rear side elevational view being a mirror image thereof;

FIG. 4 is a left side elevational view thereof; the right side elevational view being a mirror image thereof; and,

FIG. 5 is a bottom plan view thereof.

The broken lines in FIG. 3 represent environment and form no part of the claimed design. The broken lines in FIGS. 4 and 5 represent portions of the planter and form no part of the claimed design.

1 Claim, 3 Drawing Sheets
